CLAIM

The ornamental design for a swimming pool cleaner, as shown and described.

DESCRIPTION

FIG. 1 is a top left perspective view of a swimming pool cleaner;

FIG. 2 is a top right perspective view of the swimming pool cleaner shown in FIG. 1;

FIG. 3 is a bottom perspective view of the swimming pool cleaner shown in FIG. 1;

FIG. 4 is a front view of the swimming pool cleaner shown in FIG. 1;

FIG. 5 is a rear view of the swimming pool cleaner shown in FIG. 1;

FIG. 6 is a left view of the swimming pool cleaner shown in FIG. 1;

FIG. 7 is a right view of the swimming pool cleaner shown in FIG. 1;

FIG. 8 is a top view of the swimming pool cleaner shown in FIG. 1; and,

FIG. 9 is a bottom view of the swimming pool cleaner shown in FIG. 1.

The broken lines illustrate portions of the swimming pool cleaner that form no part of the claimed design.
